Primary Examiner—Nelson C. Holtje*Attorney, Agent, or Firm*—Fish & Neave; Jeffrey H. Ingerman; Joel Weiss[57] **CLAIM**

The ornamental design for a sign, as shown and described.

DESCRIPTION

FIG. 1 is a top, left, front perspective view of a sign showing our new design;

FIG. 2 is a top plan view thereof;

FIG. 3 is a right side elevational view thereof, the left side being identical;

FIG. 4 is a front elevational view thereof, the rear view being identical; and,

FIG. 5 is a bottom plan view thereof.

The subject matter shown in broken line represents unclaimed environmental structure which is shown for illustrative purposes and forms no part of the claimed design.
